RAZOR

Ed Laxo, Toledo, Ohio

Application May 31, 1940, Serial No. 337,961

5 Claims. (Cl. 30—62)

This invention relates to hand operable cutting tools, more particularly of the detachable blade type.

This invention has utility when incorporated in so-called safety razor character of shaving tools, especially as of light weight with features of ease in ready manipulation and accuracy for nice placement.

Referring to the drawing:

Fig. 1 is a side elevation of an embodiment of 10 the invention in a safety razor;

Fig. 2 is an end elevation of the handle from the left of Fig. 1, showing the pawl operating feature;

Fig. 3 is an end elevation from the right of 15 Fig. 1, showing the blade holder;

Fig. 4 is a view from the opposite side of the showing in Fig. 1, parts being broken away;

Fig. 5 is a section on the line V—V, Fig. 1, looking toward the blade holder;

Fig. 6 is a view on the line VI—VI, Fig. 3, showing the tool in longitudinal section;

Fig. 7 is a view similar to Fig. 6 with the clamp in blade releasing position;

Fig. 8 is a view on the line VIII—VIII, Fig. 6, 25 showing the blade holding clamp;

Fig. 9 is a detail view in plan of the ratchet-carrying element as engaged by the pawl; and

Fig. 10 is a detail view of the cutting edge element or blade as detachably carried in the 30 holder herein.

In carrying out this invention, a main holder embodying sheet metal or grip 1 has semi-circular or arched top 2 with parallel sides 3 and inturned bottom flanges 4 extend to abutting region 5 and thereby form tubular way 6. From this tubular way 6 there is forwardly in extension 7 to diametric terminus 8 having inclined seat portion 9 adapted to have placed therein a blade 10 having cutting edge 11, ledge-forming notched termini 12, and a straight back 13. This straight back 13 rides at the inner side of this diametric portion 8. Complemental to this seat 9 is seat 14 having side shoulders 15 to engage under the notches 12 of the blade. This seat 8, 9, and complementary seat 14 not only locate the portion 13 of the blade at the diameter region for the handle extended, but locate the cutting edge 11 of the blade in approximate tangency to the extension of the handle portions 4. Opening 16 with clearance 17 provides a way for movement of material severed by the operation of the blade.

This complementary seat member or comb is provided with shield or guide projection 18. From this complementary seat device 14 there is exten-

sion 19 approximating the diametrical region of the handle and having overhanging ears 20 cooperating with guides 21 from the handle toward the clamp seat 8, 9. There is thus a directing guide for the complementary clamp 14. This clamp 14 is at its terminus 22 away from the clamp 8, 9, engaged by ears 23 of diametrically extending tongue 24 from upstanding portion 25 of slide 26 having rear back portion 27 in the tubular handle. Compression helical spring 28 between the portion 27 and portion 29 tends normally to thrust this connection or actuator 23, 24, yieldably to hold the seat portion 14 in clamping position with the seat portion 8, 9, for engaging the blade 10 therebetween. The abutment 29 extends from base portion 30 along the inner side of the flanges 4 remote from the portion 26 riding along such flanges 4. This portion 30 has upstanding rack portion 31 and protrudes 20 beyond the handle to have upstanding ledge 32 beyond seat 33. Pivot pin 34, approximating the diameter of the tubular handle, mounts pawl 35 in position to engage the teeth of the rack 31. This pawl 35 is on the pivot pin 34 and has remote from the pawl 35 socket 36 in which is located compression spring 37 to plunger 38 against the seat 33 and thereby tends yieldably to hold the pawl 35 in engaging position with the rack 31. Upon depression of protruding portion 39 toward the seat 33 against the compression spring 37, the pawl 35 may be pulled away from the rack 31 and the spring 28 then position the rack to protrude further from the handle and thereby reduce the compression action or holding for the blade 10. This may serve as an automatic release for the blade 10 to be dropped clear of clamping position. Otherwise one may shift the portion 20 as to the handle for opening the clamp to remove, adjust, or reverse the blade 40 therein.

The device of this disclosure may be made of thin sheet material or metal. It is a light weight hand tool, convenient for accurate and ready use as well as compact for storage. The simplicity and fewness of the parts adapts such for economic production. The narrow region for the blade and its effective holding are features for economy in the use of a small portion of the high grade cutting steel or alloy for the blade. The notched ends are quick means for accurate, positive locking against casual disturbance. The clearance regions are such that material accumulated may be washed clear thereof by way of the opening 16 at the comb device.

What is claimed and it is desired to secure by United States Letters Patent is:

1. A safety razor tubular handle convex and converging on one side toward a diametrical extension terminus intersecting an axis and there forming a seat limit with said seat inclined therefrom toward the handle, said seat adapted to receive a blade having its back at said axis diameter limit and its edge approximate tangency to said handle as clearing the inclined seat, said tubular handle providing a guide, and a slide in said guide adapted to thrust toward the seat to hold the blade in the seat.

2. A safety razor comprising a tubular handle with a diametrical extension terminus forming a main seat adapted to receive a blade, a guide slide way toward said seat, a complementary seat slidable in the guide slide way, and a compression helical spring in the handle extending away from the terminus of the complementary seat remote from the blade for impelling the complementary seat to nest with the main seat and thereby adapted to clamp the blade in operative position therebetween.

3. A safety razor comprising a tubular handle with a diametrical extension terminus forming a main seat adapted to receive a blade, a guide slide way toward said seat, a complementary seat slidable in the guide slide way, a compression helical spring in the handle extending away from the terminus of the complementary seat remote from the blade for impelling the complementary seat to nest with the main seat and thereby adapted to clamp the blade in operative position therebetween, and an abutment in the handle for the spring remote from the complementary seat.

4. A safety razor comprising a tubular handle with a diametrical extension terminus forming a

main seat adapted to receive a blade, a guide slide way toward said seat, a complementary seat slidable in the guide slide way, a compression helical spring in the handle extending away from the terminus of the complementary seat remote from the blade for impelling the complementary seat to nest with the main seat and thereby adapted to clamp the blade in operative position therebetween, a rack-carrying abutment in the handle for the spring remote from the complementary seat, and a pawl pivoted in the handle and adapted to engage the rack-carrying abutment, whereby the abutment may be adjusted as to the handle in determining clamp holding action for the blade.

5. A safety razor tubular handle convex and converging on one side toward a diametrical extension terminus intersecting an axis and there forming a seat limit with said seat inclined toward and rigid with the handle, a blade in said seat having its back at said axis diameter limit and its edge approximate tangency to said handle and clearing the inclined seat, said handle providing a guide slide way toward the seat, a complementary seat slidable in the guide slide way, a compression helical spring in the handle extending away from the terminus of the complementary seat remote from the blade for impelling the complementary seat to nest with the rigid seat and thereby adapted to clamp the blade in operative position therebetween, a rack-carrying abutment in the handle for the spring remote from the complementary seat, and a pawl pivoted in the handle and adapted to engage the rack-carrying abutment, whereby the abutment may be adjusted as to the handle in determining clamp holding action for the blade.

ED LAXO.
